(57) **CLAIM**

We claim the ornamental design for a scooter with rear wheel brake, as shown and described.

DESCRIPTION

FIG. 1 is a perspective view showing my design for a scooter with rear wheel brake according to the present invention; FIG. 2 is a side view thereof;

FIG. 3 is a side view thereof opposite to that shown in FIG. 2;

FIG. 4 is a front view thereof;

FIG. 5 is a rear view thereof;

FIG. 6 is a top view thereof;

FIG. 7 is a bottom view thereof; and,

FIG. 8 is a perspective view of my design being collapsed.
